UNITED STATES PATENT OFFICE

154,463

DESIGN FOR AN EXTRUDED METAL TWIN BALL RACE MEMBER

Thorp Clive Cowdroy, Balgowlah, near Sydney,
New South Wales, Australia

Application February 5, 1948, Serial No. 144,311

Term of patent 7 years

(Cl. D54—2)

To all whom it may concern:

Be it known that I, Thorp Clive Cowdroy, a subject of the King of Great Britain and resident of Ernest Street, Balgowlah, near Sydney, in the State of New South Wales, Commonwealth of Australia, have invented a new, original, and ornamental Design for an Extruded Metal Twin Ball Race Member, of which the following is a specification, reference being had to the accompanying drawing, forming part thereof.

Fig. 1 is an end view of an extruded metal twin ball race member, showing my design, and

Fig. 2 is a perspective view thereof.

I claim:

The ornamental design for an extruded metal twin ball race member, as shown.

THORP CLIVE COWDROY.
